UNITED STATES PATENT OFFICE.

PAUL CRICCHIO, OF NEW YORK, N. Y., ASSIGNOR TO MAJESTIC LAMP WORKS, A PARTNERSHIP CONSISTING OF PHILIP SILBERHARTZ, JACOB SILBERHARTZ, AND HARRY SCHEINER, ALL OF BROOKLYN, NEW YORK.

DESIGN FOR A BOWL OR ANALOGOUS ARTICLE.

Application filed March 6, 1929. Serial No. 30,359. Term of patent 3½ years.

To all whom it may concern:

Be it known that I, PAUL CRICCHIO, a citizen of the United States, and a resident of New York, county of Bronx, and State of New York, have invented a new, original, and ornamental Design for a Bowl or Analogous Article, of which the following is a specification, reference being had to the drawing, forming a part thereof.

The single figure of the drawing shows a perspective view of the bowl or analogous article.

The form of ornament used on the back side of the bowl is the same as on the front side, except that the figure surmounting the bowl appears from the back, instead of from the front.

I claim:

The ornamental design for a bowl or analogous article substantially as shown and described.

PAUL CRICCHIO.
